UNITED STATES PATENT OFFICE

165,011

FIELD CHEST

James H. Kuhns, Winfield, Kans.

Application June 19, 1951, Serial No. 15,600

Term of patent 14 years

(Cl. D67—4)

To all whom it may concern:

Be it known that I, James H. Kuhns, a citizen of the United States, residing at Winfield, in the county of Cowley and State of Kansas, have invented a new, original, and ornamental Design for a Field Chest, of which the following is a specification, reference being had to the accompanying drawing, forming part thereof.

Figure 1 is a perspective view of a field chest, showing my new design;

Figure 2 is a side elevational view thereof;

Figure 3 is an end elevational view thereof;

Figure 4 is a perspective view of the field chest open for use;

Figure 5 is a side elevational view of the field chest open for use.

I claim:

The ornamental design for a field chest, as shown,

JAMES H. KUHNS.
